UNITED STATES PATENT OFFICE.

THOMAS F. BOWKER, OF FITCHBURG, MASSACHUSETTS, ASSIGNOR TO MARY ELIZABETH JOHNSON, TRUSTEE, OF FITCHBURG, MASSACHUSETTS.

DESIGN FOR A SCREW-DRIVER.

48,218.

Specification for Design.

Patented Nov. 30, 1915.

Application filed July 1, 1915. Serial No. 37,594. Term of patent 14 years.

To all whom it may concern:

Be it known that I, THOMAS F. BOWKER, a citizen of the United States, residing at Fitchburg, in the county of Worcester and Commonwealth of Massachusetts, have invented a new, original, and ornamental Design for Screw-Drivers, of which the following is a specification, reference being had to the accompanying drawings, forming part thereof.

Figure 1 is a plan view of a screw driver,

showing my new design. Fig. 2 is a side view of a screw driver, showing my new design.

I claim:

The ornamental design for a screw driver, as shown in the accompanying drawings.

Dated this 25th day of June, 1915.

THOMAS F. BOWKER.

Witnesses:

R. V. TOWNSEND,

ROSCOE H. LYONS.
